Inventor:

Clarence W. Taylor,

UNITED STATES PATENT OFFICE.

CLARENCE W. TAYLOR, OF OAK PARK, ILLINOIS.

COMB AND COMB-CLEANER COMBINED.

No. 820,534.

Specification of Letters Patent.

Patented May 15, 1906.

Application filed November 8, 1905, Serial No. 286,350.

To all whom it may concern:

Be it known that I, CLARENCE W. TAYLOR, a citizen of the United States, residing at Oak Park, in the county of Cook and State of Illinois, have invented certain new and useful Improvements in a Comb and Comb-Cleaner Combined, of which the following is a specification.

My invention relates to an improved comb and comb-cleaner combined.

Primarily the invention resides in certain improvements hereinafter specifically set forth upon the forms of comb and comb-cleaner described and claimed in my allowed application filed August 19, 1905, Serial No. 274,948, the objects of the invention being to provide an improved comb in which the interval cut-away portion or space intervening between the end and first tooth extends a short distance above the base of the teeth into the body of the comb, near each end thereof, and to provide a cleaner formed to have a side-embracing member and a perforated portion adapted to receive the teeth of the comb; and the invention consists of certain novel features and construction and combinations and arrangement of parts, as will be more fully hereinafter described, and pointed out in the claims.

In the accompanying drawings, Figure 1 is a view of my invention, showing the side of the comb on which the embracing portion of the cleaner is mounted. Fig. 2 is a view of the opposite side of the comb. Fig. 3 is a plan of the cleaner before it is formed. Fig. 4 is a top plan view of the cleaner after being formed to be mounted on the comb. Fig. 5 is a section on line 5 5 of Fig. 1.

Similar numerals refer to similar parts throughout the several views.

Referring to the drawings, 6 denotes the body of the comb, 7 7 indicate the interval cut-away portion or space intervening between the end and first tooth, which extends a short distance above the base of the teeth into the body of the comb near each end thereof, and 8 represents a recess or depression in one surface of the comb near each end of the same. The intervals 7 7 extend a sufficient length into the body of the comb to accommodate the width of the embracing member 9 of the cleaner when it is in normal po-

sition. The cleaner (shown in Figs. 3 and 4) is composed of an embracing part or member 9 and a perforated part or member 10. The side-embracing member 9 extends the greater part of its length on only one side of the comb, and the perforated part 10 is adapted to receive the teeth of the comb and to be held adjacent to the base of the teeth by engaging devices 13, carried by the end portions of the cleaner and depressions 8 in one lateral surface near each end of the comb. The end portions of the cleaner 11 11 are formed to be inserted between the end tooth and the second tooth at each end of the comb. The ends of the cleaner 12 12, Figs. 2 and 4, are provided with a bead or raised parts 13 13, adapted to engage the recesses 8 8 to secure the cleaner to the comb. The comb and the cleaner each may be made of any suitable material. I prefer hard rubber for the comb and an elastic metal for the cleaner to obtain spring-pressure of its ends against the surface of the comb for removable engagement therewith.

In operation when it is desired to cleanse the comb the cleaner may be pushed down, with enough force to disengage it from the comb, to the ends of the teeth and the accumulation removed. Then it may be pushed up to where it fastens to the comb.

Having thus fully described my invention, what I claim as new, and desire to secure by Letters Patent, is—

1. The combination with a comb having a depression in one lateral surface near each end thereof, of a cleaner comprising a side-embracing member the major portion of its length embracing only one side of the comb and a perforated member adapted to receive the teeth of the comb, said cleaner having its entire end portions 11 formed to pass between the end and first tooth of the comb, and the end portions 12 formed to bear only upon the opposite side of the comb and having beads 13 for spring engagement with said depressions to removably secure the cleaner to the comb.

2. The combination with a comb having a cut-away portion between the end and first tooth and extending a short distance above the base of the teeth into the body of the comb near each end thereof, of a cleaner comprising an embracing part and a perforated

part and having its end portions suitably formed to pass between the end and first tooth of the comb near each end thereof and bear only upon the side of the comb opposite to that on which the embracing part is mounted and engaging means to secure the cleaner to the comb.

In testimony whereof I affix my signature in presence of two witnesses.

CLARENCE W. TAYLOR.
